UNITED STATES PATENT OFFICE

WILLIAM RODERICK BARCLAY AND REGINALD BOYD WOODCOCK, OF LEICESTER, ENGLAND, ASSIGNEES TO UNITED SHOE MACHINERY CORPORATION, OF PATERSON, NEW JERSEY, A CORPORATION OF NEW JERSEY

MACHINE FOR USE IN THE WAXING AND BURNISHING OF LEATHER

Application filed September 16, 1927, Serial No. 219,954, and in Great Britain October 1, 1926.

This invention relates to machines for use in the waxing and burnishing of leather, and is illustrated herein as embodied in a machine for so treating leather after it has been made into shoes.

An object of the invention is to provide an improved, conveniently arranged machine for waxing and burnishing shoes. The illustrated machine comprises a wax-applying roll, a cylindrical burnishing roll having a relatively wide work-engaging face, a rotary brush, and a burnishing roll having a relatively narrow, rounded, work-engaging face, all in axial alinement and in the order stated above. A third burnishing tool in the form of a rotary pad is carried on the lower end of a forwardly extending, downwardly inclined shaft mounted in the frame of the machine and is slightly above and in front of the last-mentioned burnishing members. We have found that this arrangement of wax-supporting and burnishing tools, illustrated in the accompanying drawings, affords the maximum of convenience to the operator and enables him to handle the work more expeditiously than has heretofore been possible.

The waxes commonly used for burnishing purposes may be most conveniently applied to the work by means of rolls having absorbent surfaces upon which wax must be rendered molten. We have found that rolls having felt covered surfaces are well adapted for wax-applying purposes, but felt, being a poor conductor of heat, requires the use of a heating medium which may be raised to a high temperature. In view of these requirements and the characteristics of oil which enable it to meet them, we have found oil to be a most advantageous medium. However, when heated, the more volatile constituents of the oil are driven off, leaving a heavier heating medium which, during the later stages of its useful life, tends to congeal in the abruptly curved portions of the piping system by means of which the heating medium is conducted from a heat source to the wax-applying roll. Hence, it is desirable that the operator of the machine in which the invention is embodied be warned of a stoppage or an approaching stoppage in the

heating system. To this end and in accordance with a feature of the invention, the various parts of the illustrated waxing device are heated by oil flowing serially through them, it being apparent that a visible diminution in flow of the heating medium will indicate an obstruction in the serial piping system, since in such a system all of the heating medium must flow past all points in the system.

In order not to overheat the heating medium when the machine is not in use and to minimize the amount of attention required of the operator, means has been provided for regulating the heat supplied to the heating medium and is operated by the means for starting and stopping the burnishing rolls. To this end and in accordance with another feature of the invention, the control means provided for regulating the heat supplied to the heating medium is so connected to the driving control as to turn on the heat when the roll is started and to shut off the heat when the roll is stopped.

In accordance with another object of the invention, a novel device has also been provided for tensioning a fabric cover, such as knitted stockinet, over the felt roll of the waxing device. To this end the illustrated device comprises a hub for supporting the roll encased by the cover and constructed and arranged to clamp one end of the cover thereto, and means to grip the other end of the cover independently of the roll and to hold the cover stretched over the roll. As illustrated, the cover is stretched by the relative separation of the above-mentioned gripping means one of which may slide axially along the hub.

These and other features of the invention will be more fully understood from the following description of the machine in which the invention is shown as embodied, and will be finally pointed out in the claims.

In the accompanying drawings,

Fig. 1 is a front elevation of one illustrative machine according to the invention;

Fig. 2 is a right-hand side elevation of the machine;

Fig. 3 is a side elevation of a burnishing roll and dust hood of the machine;

Fig. 4 is a longitudinal section through a waxing roll and associated wax-spreading roll of the machine, and

Fig. 5 is an elevation showing a heating arrangement for the waxing roll.

One illustrative form of machine (which in the following description will be considered as being viewed from the front) comprises 10 left-hand and right-hand side frames 1 and 2 extending rearwardly and joined together by tie members (not shown) and by a table 4 fixed to the top of the side frames. Each 15 side frame near the bottom thereof carries a bearing for a driving shaft 201 extending across the machine. This shaft carries fast and loose pulleys for a belt by which it is driven and has on it various pulleys for driving the various devices of the machine.

The table 4 at the top of the side frames supports the various operative instrumentalities of the machine. At the right-hand side of the machine is a waxing roll 5 for applying 25 wax to the shoe bottom. At the left of the waxing roll and some four inches from it is a bottom burnishing roll 6, axially in alignment with the waxing roll 5, for burnishing the shoe bottom at the heel and sole. Next to the 30 burnishing roll at the left thereof and some two and a half inches away from it in that direction is a rotary pad 7 for burnishing the waist of the sole close to the breast and the breast face of the heel, the rotary pad being 35 above and in front of the waxing and burnishing rolls and its axis being upwardly and rearwardly inclined at an angle of some 60° to the horizontal. At the left of the rotary pad and some four inches from it is a rotary 40 brush 8 for brushing the shoe bottoms after they have been waxed and burnished. This brush is some three and a half inches wide and some ten inches in diameter at its left-hand end and is tapered towards the right to a 45 diameter of some eight inches so that the large end of the brush may enter the angle between the breast face of the heel and the face of the sole at the waist. At the left of the brush 8 and some five inches from it is a 50 burnishing roll 9 for burnishing that part of the waist of the sole which cannot be operated upon by the roll 6.

The bottom burnishing rolls 6 and 9 and the brush 8 are fixed on a roll carrying shaft 55 10 which extends across the machine parallel to the driving shaft and which is rotatably mounted in two bearings 11 and 12 carried by a pair of brackets 13, 14 fixed on the table 4. The bearing 14 is positioned between the 60 bottom burnishing roll 6 and the tapered brush 8 and the other bearing 13 at the left of the brush 8 and between that brush and the roll 9. A pulley 15, fixed on the shaft 10 between the bearing 12 and the tapered brush 65 8, is connected by a belt to a pulley on the

driving shaft 201 and the roll carrying shaft is driven at a speed of about 950 R. P. M.

The brush 8 is partially enclosed in a metal hood 16 which is connected by piping to a fan (not shown), fixed on the right-hand side frame 1 and driven from the driving shaft, 70 to carry away dust from the brush.

The rotary pad 7 is a convex disk pad of a type ordinarily used for buffing the portions of the soles of shoes immediately adjacent to their heel breasts, a cloth cover being used instead of the ordinary abrasive cover. The pad 7 is fixed on the lower end of a spindle 17 which is upwardly and rearwardly inclined and the centre of the lower face of the pad is 75 some six inches in front of the vertical plane through the axis of the roll shaft and some four and a half inches above the horizontal plane through that axis. The spindle 17 is 80 rotatably mounted in bearings in a block 18 fixed on the forward upper end of an arm 19 which is fixed at its lower end to the top of the bracket 14. Between the bearings on the block 18 are fast and loose grooved pulleys 20, 21 for a round belt which passes over 85 guide pulleys 22 carried by a rearwardly extending part of the arm 19 and round a 90 grooved pulley on the driving shaft. The pad 7 is driven at a speed of about 2300 R. P. M. A belt shifter mounted on the block 18 enables the operator readily to stop the pad 95 without stopping the rest of the machine if he desires to renew the cloth cover.

The bottom burnishing roll 6 is about seven and a half inches in diameter and about four and a half inches wide and comprises a sleeve, 100 fixed on the roll shaft 10, having fixed on it a felt roll covered with stockinet. A hood 23 partly encircles the burnishing roll and has a pipe 24 connecting the hood to the previously 105 mentioned dust extracting means. A heating member (e. g. a gas burner) is situated inside the hood near the back of the hood and below the roll for warming the surface of the pad and the dust extracting pipe 24 has in 110 it a slide 25 for closing the pipe near the exit from the hood so that the heating member and the dust extracting device may be used either singly or together. The front portion 26 of the hood is pivoted at 127 (Fig. 3) to the hood 23 so that the portion 26 may be swung up 115 out of the way when it is desired to change the cover of the roll. The burnishing roll 9 is 120 some seven and a half inches in diameter and is about one inch wide and is covered with stockinet. It has a convex surface, the radius of curvature in section of which is substantially less than the radius of the roll, owing to 125 the relative shortness or narrowness of the roll. This form of roll enables it to operate upon portions of the shank and of the heel breast which would be inaccessible to roll 6. The waxing roll 5 is some six and a half 130 inches long and some three inches in diameter and comprises a tubular stockinet cover 27

on a felt foundation 28 which is fixed on a inner surface of the casing 49 where it passes metal sleeve 29. The ends of the cover 27 are clamped against a flange 30 formed on one end of the metal sleeve 29 and a flange 31 keyed on the other end of the sleeve.

The ends of the cover are clamped against the flanges 30, integral with the hub, and 31 independently adjustably along the sleeve 29 by collars 32, 33 loosely mounted on tubular extensions 34, 35 of the flanges 30, 31. The collars 32, 33 are pressed towards the flanges 30, 31 to clamp the ends of the cover by nuts 36, 37 threaded on the extensions 34, 35. Threaded on the end of the extension 35 is a nut 38 which bears against the end of the sleeve 29 and by adjustment of which nut the extension 35, flange 31, collar 33, and nut 37 may be drawn axially along the sleeve and outwardly with respect to the end face of the waxing roll 5 to stretch the cover 27 lengthwise. A collar 39 is fixed on the shaft 40, on which the sleeve 29 is rotatably mounted, to prevent endwise movement of the sleeve and the nut 38 on the shaft. The roll 5 is driven by a chain passing round a sprocket wheel 41 which is screwed on to an adapter 42 into which is pressed one end of a sleeve 43 rotatably mounted on the shaft 40. The adapter has on it a key 44 which enters a groove in the end of the extension 34 to make a driving connection between the adapter 42 and sleeve 29. By removing the collar 39 the sleeve and the parts carried by it may be drawn off the shaft 40 without disturbing the driving connection of the sprocket wheel 41. The shaft 40 is clamped in a bracket 45 (Fig. 2) fixed on the right-hand end of the table 4. The chain which passes over the sprocket wheel 41 passes round a second sprocket wheel on a countershaft 203 (Fig. 1) mounted in a bearing on the right-hand side frame 1. The countershaft 203 is driven by a belt from a pulley on the driving shaft of the machine and relative sizes of the pulleys on the driving shaft and countershaft and of the sprocket wheels are such that the waxing roll is driven at about 155 R. P. M.

Above the waxing roll 5 is a metal roll 46 which is pressed against the surface of the roll 5 to form the latter in its original shape if it has been distorted by the application of the work against it and to distribute the wax. The wax-spreading roll 46 is rotatably mounted on an eccentric portion 47 (Fig. 4) of a sleeve 48 which is rotatably mounted in a casing 49. The sleeve 48 at one end has projecting from it an arm 50 carrying a spring pressed plunger 51 which is arranged to enter one of a series of holes 52 (Fig. 2) formed in a segment 53 on the casing 49. By pulling out the plunger 51 and rotating the sleeve 48 the roll 46 may be raised out of or lowered into contact with the roll 5 and movement in either direction is limited by a pin 54 in the casing 49 and stops 55, 56 on the sleeve 48. The

70 behind the roll 5 is covered by a detachable metal sheet 72 which engages the roll 5 and prevents wear on the casing. The surface of the sheet nearest the roll 5 is curved to substantially the same radius as the outer surface of the roll 5 so that if the surface of the sheet is moved into or nearly into engagement with the roll the roll will be heated by the casing, the casing being heated as hereinafter 75

described. The casing 49 is fixed to a slide 57 which is mounted in a guideway formed in the bracket 45 which carries the roll 5. The casing 49 is fixed to the slide 57 by bolts 58 fixed in the slide 57 and passing through arcuate 80 slots 59 in the casing so that when the bolts are slackened the casing may be swung about the roll 5. The guideway extends rearwardly and upwardly at an angle of some fifteen degrees to the horizontal. The slide 57 is 85 clamped in the guideway by a thumb-screw 60 threaded through the slide and engaging the bottom of the guideway. A screw 61 is threaded through a lug 62 on the slide 57 and engages the bracket at the rear end of the 90 guideway to limit forward movement of the casing towards the waxing roll. A handle 63 is fixed on the slide by which the casing may be moved rearwardly and forwardly.

The waxing roll 5 and the roll 46 may be 95 heated by a hot oil circulating system. The oil is heated in a coiled-tube heater 101 (Fig. 5) carried by a bracket fixed to the right-hand side frame near the bottom of the frame. From the heater 101 a pipe 64 passes upwardly to the lower end of the casing 49. A pipe 65 leads from the casing, to the right-hand end of and through the sleeve 48 on which the roll 46 is mounted and from the left-hand end of the sleeve upwardly and then downwardly to a reservoir 66 carried by the bracket 45 which carries the waxing roll 5. A baffle (not shown) within casing 49 prevents the direct passage of fluid from pipe 64 to pipe 65 and thus insures circulation through casing 49. From the reservoir 66 a pipe 67 leads to the top left-hand end of the shaft 40. The shaft 40 is bored axially and fixed in the bore 100

is a metal strip 68 which divides the bore into two passages 69, 70 so that oil passing down the pipe 67 travels along the passage 69 and then back along the passage 70. A pipe 71 leads from the passage 70 back to the heating coil 101. The reservoir 66 and pipe leading to it permit the casing 49 and roll 46 to be moved away from the roll 5 when desired. An oil pump 103, inserted in the return pipe 71, is fixed below the heater 101, to the bracket which carries the heater and is driven from a pulley fixed on the countershaft 105 through which the waxing roll is driven. It will be noted that in the above arrangement the oil is conducted serially through the various passages, thereby insuring a full supply of heat to both rolls.

5 The oil is heated by a gas burner 105 the supply cock 107 of which is connected by a link 111 (Fig. 1) to the hand lever 113 of the usual belt shifter of the machine so that the gas is turned off when the machine is stopped and is turned on again when the machine is started. An ordinary pilot light 109 is employed for igniting the burner 105.

10 The rotary pad 7 for burnishing the waist of the sole and breast of the heel may be covered with a fabric such as is used for shoe linings and has a suede finish on one face, the latter face constituting the working face of the covered tool.

15 In using the machine the worker preferably holds the shoe throughout the finishing operation with the forepart of the upper (on the last) in his left hand and with his right hand grasping the heel end of the shoe. 20 Holding the shoe thus' bottom upwards he moves it to and fro (with the toe end more or less rearward) in contact with the lower or lower front portion of the waxing roll 5 to distribute wax, which he has previously applied to the roll by holding a lump of wax against it and by moving it along the roll over the shoe bottom, and having done this to his satisfaction without any substantial change of his general position, he presents the shoe 25 in the same way to the bottom burnishing roll 6 (which is kept warm as hereinbefore described if it is desired to use a heated roll) and burnishes the forepart and as much as he can of the waist by this roll. Then he burnishes that part of the waist which cannot be 30 operated upon by the roll 6 by presenting the shoe to the roll 9. He then and still without substantial change of his general position or of his manner of presenting the shoe, 35 presents the latter to the rotary pad 7 and thereby burnishes that portion of the waist which the presence of the heel and the size and shape of the bottom burnishing rolls prevented him from burnishing on the latter. He 40 may also use the edge of the covered rotary pad 7 to burnish the heel breast or by suitable change of his presentation of the work use the top surface of the covered pad for that purpose. If he prefers he may use the rotary pad before using the bottom burnishing roll.

45 The use of the roll 9 will depend upon the size of the waist portion not reached by the roll 6. In some cases it may be found that the portion remaining to be burnished can be 50 effectively operated upon by the pad 7, in which case the roll 9 will not be used. If the portion remaining to be burnished is comparatively large the roll 9 will be used to burnish as much as possible of this portion and 55 the pad 7 may then be used to burnish up to the heel and also, if desired, the heel breast.

60 After having burnished the shoe bottom and the heel breast he gives these parts a final polish with the brush 8 still holding the 65 shoe in the same general way.

The arrangement of the various devices in the cases described is such as regards their sequence from right to left and their actual disposition that, holding the shoe in a natural way, the operator can speedily and with a minimum of change in his mode of holding the shoe and of his actual stance present the work to the requisite tools and perform the requisite operations in an exceedingly convenient order.

Having described our invention what we claim is new and desire to secure by Letters Patent of the United States is:

1. A roll for applying wax to leather or for burnishing leather, comprising a hub, a 80 felt roll mounted on said hub, a stockinet cover for said felt roll, means for clamping one end of said cover to the hub, and means to grip the other end of the cover independently of the roll and to hold the cover stretched 85 over the roll.

2. A tool for burnishing leather comprising a hub, a felt roll mounted on said hub, and a cover surrounding said roll and attached at one end to said hub and at the other end 90 to a gripping means axially slidable on said hub to tension said cover over the roll.

3. A wax applying tool comprising a hub, a felt roll supported by said hub, a fabric cover for the roll, means on said hub at either 95 side of said roll for gripping said cover, said means being constructed and arranged for relatively free axial movement to tension the cover over the roll, and means for holding said gripping means relatively fixed.

4. A wax applying tool comprising a felt roll, a fabric cover for the roll, a hub supporting said roll and constructed and arranged to grip one end of said cover, gripping means for the other end of the cover slidably mounted on said hub, and means for adjustably separating said gripping means to tension the cover over the felt roll on said hub.

5. In a machine for waxing leather, a hub adapted to carry a wax-applying roll, means carried upon each end of said hub for gripping a cover for said roll, one of said gripping means being splined upon said hub and having a threaded portion extending longitudinally of the axis of the hub, and a threaded member adapted to engage said threaded portion of said gripping member and to be held by said hub against motion longitudinally of the axis of said hub, whereby rotation of said member will serve to adjust said gripping members mutually in longitudinal relation to tension the cover.

6. In a machine for waxing leather, a hollow shaft, a hub mounted on said shaft, a 125 felt roll carried by said hub, a fabric cover for said roll, cover-gripping means carried at each end of said hub, said means being mutually adjustable longitudinally of the axis of the hub to tension said fabric cover, 130

and means for conducting a heated fluid through the interior of said shaft.

7. A machine for applying wax to leather, comprising a wax-applying roll, means for driving said roll, control means for starting and stopping said driving means, means for supplying heat to said roll, and control means for said heat supply actuated by the operation of said driving control means.

10 8. A machine for applying wax to leather, comprising a wax-applying roll, means for driving said roll, control means for starting and stopping said driving means, a circulatory system having a portion of heat-exchange relation to said roll, means for circulating a fluid through said system, a source of heat for said fluid, and control means for said source and so connected to said driving control as to turn on the heat when the 15 roll is started and to shut off the heat when the roll is stopped.

9. A machine for applying wax to leather, comprising a wax-applying roll, a drive shaft for said roll, driving connections between 25 said roll and said shaft, a circulatory system for a heated fluid having a portion in heat-exchange relation to said roll, a heater for the fluid in said system, a pump for circulating the fluid in said system, and driving connections between said pump and said shaft.

30 10. A machine for waxing leather, comprising a wax-applying roll adapted to be coated with wax for application to the leather, a wax-spreading roll engaging said wax-applying roll, and means for supplying a heated fluid serially into heat-exchange relation to said rolls.

11. A machine for waxing leather, comprising a wax-applying roll adapted to be 40 coated with wax for application to the leather, a wax-spreading roll, each of said rolls being adapted to conduct a fluid, means for rotatably supporting said rolls in mutual engagement, and means for conducting a heated fluid serially through said rolls.

12. A machine for waxing leather, comprising a wax-applying roll adapted to be coated with wax for application to the leather, a wax-spreading roll, each of said rolls 50 being adapted internally to receive a supply of fluid, supporting means for said rolls permitting relative movement between said rolls into and out of a position of mutual engagement, and means for supplying a heated fluid serially to said rolls.

13. A machine for waxing leather, comprising a pair of substantially parallel hollow axles, a wax-applying roll mounted on one of said axles and adapted to be coated 60 with wax for application to the leather, a wax-spreading roll mounted on the other said axle and adapted to engage said wax-applying roll, and means for circulating a heated fluid serially through said axles.

35 14. A machine for waxing leather, com-

prising a pair of substantially parallel hollow axles, a wax-applying roll mounted on one of said axles, an eccentric sleeve mounted on the other said axle, a wax-spreading roll rotatably mounted on said sleeve whereby rotation of the sleeve will bring the said wax-spreading roll into and out of engagement with the said wax-applying roll, and means for circulating a heated fluid serially through said axles.

75 In testimony whereof we have signed our names to this specification.
